(No Model.)

L. D. NEWELL,

SELF LEVELING BERTH.

No. 256,239.

Patented Apr. 11, 1882.

INVENTOR,

Scorzenzo-Tom Hewell

UNITED STATES PATENT OFFICE.

LORENZO D. NEWELL, OF PROVIDENCE, RHODE ISLAND.

SELF-LEVELING BERTH.

SPECIFICATION forming part of Letters Patent No. 256,239, dated April 11, 1882.

Application filed July 20, 1881. (No model.)

To all whom it may concern:

Be it known that I, LORENZO D. NEWELL, a citizen of the United States, residing at Providence, in the county of Providence and 5 State of Rhode Island, have invented certain new and useful Improvements in Ships' Oscillating Berths and Sofas; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 My invention relates more particularly to improvements on ships' berths, which were granted to me in the United States September 10, 1872; and also in Great Britain 1873, Patent No. 503.

20 My present invention consists in the peculiar manner of securing the berth to the vibrating frame; also, in the arrangement for adjusting the sliding counter poise or weight; further, in the means for securing the berth in 25 position when not in use, &c.; and, finally, in the arrangement of the top and sides of the berth for excluding from sight the motion of the vessel.

In the accompanying drawings, in which 30 similar letters of reference indicate corresponding parts, Figure 1 shows a front side view of the berth, partly in section, as placed "fore-and-aft" in a vessel, together with adjacent sides of a state-room. Fig. 2 is a vertical 35 transverse section of the same on line X X of Fig. 1. Fig. 3 shows the form and arrangement of the sliding oscillating frame, and is a vertical transverse section of berth on line O O, Fig. 1. Fig. 4 is a vertical longitudinal 40 section on line Y Y of Fig. 3, enlarged scale. Fig. 5 is a horizontal section on line X X X X of Fig. 4, also enlarged. Fig. 6 shows the sliding counter-weight.

These berths, &c., are suspended in a frame 45 having "universal motion," so called, which in turn is supported upon a sliding bearing secured to the sides or walls of the state-room, and is more fully described in the patents granted to me above referred to.

50 The following is a more detailed description of the parts constituting my invention:

A represents the suspended berth, vibrating

in its transverse axis upon pins F, secured to the skeleton frame B, having attached thereto plates C, which form the ends of said skeleton 55 frame B.

D are plates secured to opposite sides of the state-room, upon which the sliding plates or bearings D' are mounted, which are fitted to receive the slotted projecting journal or hub 60 E, as shown in Fig. 4, which forms the longitudinal axis of the berth.

To the ends of the berth, at the center thereof, are inserted the tongued or T-shaped pieces G, curved to a segment of a circle having its 65 center or fulcrum at F, and engaging with the face of the journal E of the frame C, as shown in Fig. 5. The counter-weight K, resting loosely upon the parallel pieces L, has gear-teeth 70 formed upon its under side, which are made to engage with the pinion-gear k', mounted upon the shaft k, at the center of the berth.

e represents pins attached at each end of the berth, which serve to lock the berth and frame B together by inserting said pins through the 75 ends of the berth and into the hole e' of the plate C. The thumb-screws d, which are attached to the lower projection of the sliding bearing D', are tapped into the stationary frame D, and serve to retain the sliding frame 80 in position.

The sides of the berth are hung with curtains, while the top is covered with canvas f or other suitable material, thus effectually shutting out the motion of the vessel. 85

The operation and advantages of my invention are as follows:

By having the curved T-shaped pieces G at the ends of the berth made to engage freely with the grooved journals E of the end pieces, 90 C, I wholly obviate the jar or trembling motion incident to suspended berths at the ends thereof during the voyage, due to the action of the propeller, or otherwise. These guides also have a further advantage in reducing the strain 95 upon the pins F, which might be caused by a person inadvertently pushing or pulling at the ends of the berth, instead of the frame B, when it is necessary to place the berth in position.

Another advantage of my berth consists in 100 making the under side of the end pieces, C, together with the top side of the sliding bearing D', beveled or angular, and by having them, together with the journals E, in the same ver-

tical plane, (see Figs. 3 and 4,) I am enabled to make the berths longer than they could be if the journals or pivots projected wholly from the sides of said end pieces.

5 Still another improvement consists in beveling the under side of my berth near each end, as shown at A', Fig. 1, whereby the berth can be suspended somewhat nearer the floor of the state-room, thereby enabling me to suspend 10 another berth above it, and consequently economizing space aboard the vessel.

When the berth is not in use it is designed to be moved back against the side of the room, the pins *i* resting in the sockets *i'* of the cleat 15 *I*, and in conjunction with the sliding bolt *b* the berth is rigidly secured to the vessel.

When from any cause it is desirable to secure the berth to the wall of the state-room, or, in other words, to have the motion of the berth 20 coincident with the motion of the vessel, I then lock the frame *B* to the walls of the room by means of the sliding bolt *b*, which enters the piece *b''*, Fig. 2, let into said walls, thereby conveying the rolling motion, if any there 25 be, of the vessel to the berth; and by inserting the pins *e* at each end of the berth into the frame *C* the pitching motion of the vessel, if any, is also conveyed to the berth, when the berth's motion becomes coincident, as before 30 stated, with that of the vessel. By simply withdrawing the bolt *b* and pins *e* the berth again becomes stationary as compared with the vessel's action.

The sliding weight or counterpoise *K* is made to change the center of gravity of the berth at 35 the occupant's will by simply turning the shaft *k* in the necessary direction by means of a removable wrench, which also fits the sliding bolts *b*, as shown in dotted lines in Fig. 1.

Having thus described my invention, what 40 I claim as new, and desire to secure by Letters Patent, is—

1. In combination with a self-leveling berth for vessels, the curved T-shaped strips *G* and grooved journals *E*, substantially as shown and 45 described.

2. In a self-leveling berth for vessels, the combination of the toothed counter-weight *K* with the pinion *k'* and shaft *k*, said shaft being adapted to receive a removable wrench, and 50 arranged to be operated by the occupant of the berth, substantially as shown and described.

3. In a self-leveling berth for vessels, the combination of the swinging frame *B*, the ends *C* thereof having inwardly-projecting grooved 55 journals *E*, with the sliding bearing *D'* and stationary bearing *D*, substantially as shown and described.

In testimony whereof I have affixed my signature in presence of two witnesses.

LORENZO DOW NEWELL.

Witnesses:

GEORGE T. BROWN,
GEO. H. REMINGTON.
